UNITED STATES PATENT OFFICE.

ALFRED J. MURPHY, OF CHICAGO, ILLINOIS.

STAIR-CARPET CUSHIONER.

Application filed January 23, 1928. Serial No. 248,915.

This invention relates to improvements in stair carpet cushioners and it consists of the matters hereinafter described and more particularly pointed out in the appended claims.

5 It is desired in the use of carpeted stairs to provide a cushioning means between the carpet and stair treads, so that the stairs are easier to ascend or descend and so that footsteps thereon are rendered more quiet and 10 less annoying. Such means as are at present employed usually consist of a yielding pad of cotton or like filler which disintegrates in use and absorbs dust and dirt so that the stair carpet not only wears out 15 quickly but becomes unsanitary.

The primary object of the invention is to provide a simple and efficient device adapted to be interposed between a stair step or tread and carpet, which will cushion the 20 footsteps upon the stairs and which will reduce the wear on the carpet and will be sanitary as it is incapable of absorbing and holding dust and dirt particles.

Another object of the invention is to provide a device of this kind which comprises 25 coacting sheet metal plates operatively connected together in a manner making them relatively yieldable without relative shifting, with one plate engaged upon the stair 30 step or tread and the other covered by the stair carpet.

These objects of the invention, together with others as well as the many advantages thereof will more fully appear as I proceed with my specification.

In the drawing:

Fig. 1 is a vertical sectional view through some of the steps of a flight of stairs to which my improved cushioners have been applied beneath the carpeting thereon.

Fig. 2 is a view in end elevation of one of my improved cushioners on an enlarged scale.

Fig. 3 is a top plan view thereof on a reduced scale with parts broken away to more clearly illustrate the construction thereof.

Referring now in detail to that embodiment of the invention illustrated in the accompanying drawing and especially to Fig. 50 1 thereof, 1—1 indicate the steps or treads and 2—2 indicate the risers of a flight of stairs of ordinary construction. When such stairs are embodied in a dwelling house it is often-times desirable to carpet the same, 55 not only for the sake of appearance but also to silence to some extent the sound of foot-

steps thereon. Such a carpet 3 as is shown in Fig. 1, is in the form of a strip which is secured in place in any suitable manner to the bottom margin of each riser as by a 60 tacking strip or by a rod 4 removably secured in eyelets 5 threaded in place in the riser. From the rod or tacking strip, the carpet extends over the step or tread and down over the front edge thereof to the next 65 strip or rod on the step below and so on. In some instances a soft yieldable pad of 70 felted cotton is disposed between the carpet and step or tread but this pad easily disintegrates in use, is unsanitary in that it absorbs and holds dust and seems to make the carpet wear out quickly.

My improved cushioner which is best indicated as a whole by the numeral 6 is made entirely of metal and comprises top and bottom elongated rectangular, metallic plates 7 and 8 respectively, each of the same shape and approximate area as the steps or treads with which they are used. The front margin of the bottom plate is bent over to provide a lip or flange 9 that engages the front edge of the step or tread, which front edge normally projects beyond the plane of the riser just below the same. The rear edge of the top plate as shown herein is bent over toward the underside thereof to form a hook flange 10 to receive the rear edge margin of the bottom plate with a hinge effect, while the front margin of the top plate is bent over to form a lip or flange 11 that has an edge-like engagement with the front face of the lip or flange 9 of the bottom plate. I also provide between said plates a plurality of laterally spaced yielding devices which may take the convenient form of spring fingers 12 each fixed at its rear end to the bottom plate near its rear edge, and each with its front end bowed upwardly to engage the underside of the top plate at a point spaced inwardly from the lip 11 thereof. When such a cushioner is placed upon a step or tread it will be apparent that the carpet above the same is slightly tilted downwardly toward the rear, the front end of the cushion exerting a gentle upward thrust or pressure on the carpet which holds the carpet taut and smooth between adjacent holding rods 4—4 so that no wrinkles can form therein. Under pressure of a footstep the top plate moves toward the bottom plate with a yielding action in the manner of a cushion and when such pressure is released the top plate

immediately returns to its normal position. Thus these plates act in the manner of a bellows to ventilate the carpeting each time they are stepped upon. Another feature is this: When footstep pressure is imposed upon the carpet, the lip 11 slides over the lip 9 and that part of the carpet covering the same moves therewith so that instead of the wearing action taking place between the carpet and the person's shoes, as is generally noticed when the carpet passes over the front edge of the step tread, this action is transferred to the said lips. Thus the life of the carpet is not only prolonged but it is maintained in a cleaner and more sanitary condition. It is not necessary to the intended purpose of the cushioner that the bottom plates be nailed or tacked to the steps or treads but this may be done if desired, as the carpet will hold the device in position and prevent relative endwise shifting between the plates.

The devices may be readily made in great numbers without the use of expensive machinery. They are simple in construction and efficient in operation and not only add to the comfort of a home in which they are installed but prolong the life and maintain a sanitary condition in the carpet.

While in describing my invention I have referred in detail to the form and arrangement of the parts thereof the same is to be considered as illustrative only so that I do not wish to be limited thereto except as may be pointed out in the appended claims.

35 I claim as my invention:

1. A device of the kind described comprising a top plate and a bottom plate operatively connected together along one margin, a lip on the other margin of the bottom plate, 40 a second lip on the top plate adapted to en-

gage the first lip and yielding means interposed between said plates.

2. A device of the kind described comprising a top plate and a bottom plate operatively connected together along one margin, 45 a lip on the other margin of the bottom plate, a second lip on the top plate adapted to engage the first lip and laterally spaced springs fixed at one end to one of said plates and operatively engaging at the other ends 50 with the other of said plates.

3. A device of the kind described comprising a top plate and a bottom plate, one of said plates having a hook flange at its rear to receive the rear edge of the other plate, a 55 downwardly directed flange at the front margin of the bottom plate, a similar flange at the front margin of the top plate and adapted to engage the first mentioned flange and spring means interposed between said plates and fixed at one end to one of said plates and engaged at the other end to the other of said plates.

4. A device of the kind described comprising a top plate and a bottom plate, one of said plates having a hook flange at its rear to receive the rear edge of the other plate, a 60 downwardly directed flange at the front margin of the bottom plate, a similar flange at the front margin of the top plate and 65 adapted to engage the first mentioned flange and a plurality of laterally spaced spring fingers each fixed at one end to the rear margins of the bottom plate and each engaging at the other end with the top plate near the 70 front margin thereof.

In testimony whereof, I have hereunto set my hand, this 19th day of January, 1928.

ALFRED J. MURPHY.
